Primary Examiner — George D. Kirschbaum*Assistant Examiner* — Kendra Leslie Hamilton(74) *Attorney, Agent, or Firm* — Schwartz Law Firm, P.C.(57) **CLAIM**

We claim the ornamental design for a wine straw, as shown and described.

DESCRIPTION

FIG. 1 is a left side elevational view of a wine straw, showing our new design enlarged for clarity of disclosure; FIG. 2 is a rear elevational view thereof; FIG. 3 is a front elevational view thereof; FIG. 4 is a top plan view thereof; FIG. 5 is a bottom plan view thereof; FIG. 6 is a right side elevational cross-sectional thereof, taken in the direction of line 6-6' of FIG. 5, enlarged for clarity of disclosure; FIG. 7 is a bottom rear perspective view of the wine straw of FIG. 1, shown in condition for use; and, FIG. 8 is a cross-sectional view taken in the direction of line 8-8' of FIG. 1, enlarged for clarity of disclosure. The broken line showing of a wine glass in FIG. 7 depicts environmental matter that forms no part of the claimed design.
